UNITED STATES PATENT OFFICE.

JOHN A. CLARK, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DOBBY FOR LOOMS.

SPECIFICATION forming part of Letters Patent No. 741,225, dated October 13, 1903.

Application filed June 20, 1903. Serial No. 162,306. (No model.)

To all whom it may concern:

Be it known that I, JOHN A. CLARK, a citizen of the United States, residing at Worcester, in the county of Worcester and State of Massachusetts, have invented certain new and useful Improvements in Dobbies for Looms, of which the following is a specification.

My invention relates to a doby for looms, and more particularly to improvements in the construction of a doby as now ordinarily made.

The object of my invention is to make a doby of improved construction and in which some of the parts may be readily and quickly taken apart and put together and individually detached without removing the other parts.

My invention consists in certain novel features of construction of my improvements in a doby, as will be hereinafter described.

Referring to the drawings, Figure 1 is a side view of a doby embodying my improvements. Fig. 2 is a central vertical section through the doby-frame and parts shown in Fig. 1. Fig. 3 is a vertical section taken at a point indicated by line 3-3, Fig. 1, looking in the direction of arrow *a*, same figure. Fig. 4 is a plan view of the parts shown in Fig. 2 looking in the direction of arrow *b*, same figure.

In the accompanying drawings, 1 is the doby-frame, on which the several parts of the doby mechanism are supported, as is customary.

2 represents the harness jacks or levers, pivotally supported at their lower ends on the transverse rod 3. The levers 2 have a slot 2' therein, through which extends a stationary transverse rod 4 to limit the pivotal motion of the levers 2 in the ordinary way.

5 represents rocker-levers fast on the ends of the rocking shaft 6, mounted in bearings in the frame 1.

A rocking motion is communicated to the shaft 6 through connections from some driven part of the loom to the arm 6', fast on one end of the shaft 6.

The rocking levers 5 are connected at their upper and lower ends through links 7 with the upper and lower lifter-bars 8, which have

a reciprocating motion in slots 1' in the frame 1.

Each harness lever or jack 2 has pivotally supported thereon a connector 9, and to the upper end of each connector 9 is pivotally attached an upper hook 10, and to the lower end of each connector 9 is pivotally attached a lower hook 11.

The two transverse bars 2'', which are preferably inclined toward one end, as shown in Fig. 4, act as stops for the upper and lower ends of the connectors 9.

12 is the pattern cylinder or barrel, having pins 12' thereon to engage with and operate the indicator-levers.

All of the above parts may be of the ordinary construction.

I will now describe my improvements.

I provide a series of individually-removable and vertically-extending rods or bars 13, between which the upper and lower hooks 10 and 11 extend and are guided. The lower ends of the guide-rods 13 are supported on a transverse bar 14, which is provided with a division 14' to space the lower ends of the rods 13 and form individual recesses 14'' for said rods. In connection with the transverse supporting-bar 14 is a second transverse bar 14^a, which extends parallel with the bar 14 and is preferably made integral therewith, and in this instance has a series of recesses 80 therein—one for each of the guide-rods 13—to keep the lower ends of the rods 13 in the recesses in the supporting-bar 14.

The transverse bars 14 and 14^a, preferably made integral, are secured between the side frames of the doby by bolts 15, extending through projections on the ends of the transverse bar 14^a, as shown in Fig. 3.

At transverse guide-bar 16 extends between the side frames of the doby and is secured at its ends by bolts 17, as shown in Fig. 3. The guide-bar 16 is provided with a series of holes 16' therein, through which the upper ends of the guide-rods 13 extend, as shown. Extending over the guide-bar 16 and over the upper ends of the guide-rods 13 is a transverse bar 18, which preferably has a lip on one edge 18' and is pivotally attached at one

end by a bolt 19 upon the upper part of the frame of the dobby. The other end of the bar 18 has an open end slot 18" therein to receive a bolt 20, which is screwed down to hold the bar 18 in place over the upper ends of the guide-rods 13 to hold said guide-rods in position, as shown in Fig. 2.

It will be seen that by using the guide rods or bars 13, between which the upper and lower hooks 10 and 11 extend and are guided, the upper and lower grates ordinarily used for the hooks are dispensed with, and any one of the guide rods or bars 13 may be easily removed or replaced by detaching one end of the transverse bar 18 and moving it on its pivot-support to release the upper ends of said rods or bars, as shown in Fig. 4.

Extending over the pattern barrel or cylinder 12 are a series of pattern indicators or levers 21, pivotally supported on a transverse rod 22 and resting at their outer ends on a stop-bar 23 and guided between vertical pins or guides 24 on said stop-bar 23 in the ordinary way. In this instance each of the indicator-levers 21 is provided at its inner end with an upturned portion 21', which is adapted to engage directly with the lower hook 11, and each of the indicator-levers 21 is also provided at its inner end with a downward projection 21", having a socket or recess 21''' therein to hold and support the lower end of a lifting wire or rod 25, which at its upper end extends through one of the recesses 16' of the transverse guide-bar 16 and is then bent over and extends through the adjoining recess 16' in said bar 16, as shown in Fig. 3.

On the hook or bent portion of the guide wire or rod 25 is preferably supported a small roll 25', upon which rests one of the upper hooks 10, as shown in Fig. 3.

The lower transverse bar 14^a has a series of divisions 14^{a'} on its outer surface, forming recesses 14^{a''} (see Fig. 3) to receive and guide the upturned ends 21' of the indicator-levers 21. (See Fig. 2.)

Extending below the transverse bar 14 is a transverse bar 14^b, which is preferably made integral with the transverse bars 14 and 14^a. The bar 14^b acts as a stop-bar for the inner ends 50 of the indicator-levers 21 to prevent the outer ends of said indicator-levers being raised sufficiently to allow the lower ends of the lifting rods or wires 25 being displaced from the sockets 21" on the inner ends of said indicator-levers.

The advantages of my improvements will be readily appreciated by those skilled in the art.

By means of the guide wires or rods 13 for 60 the upper and lower hooks 10 and 11 and the removable bar 18, extending over the upper ends of said guide-rods, any one of the upper or lower hooks 10 and 11 can be readily and freely lifted at their free ends for any purpose. The several parts of the dobby mechanism can be readily assembled and taken apart.

It will be understood that the details of construction of my improvements may be varied, if desired.

Having thus described my invention, what I claim as new, and desire to secure by Letters Patent, is—

1. In a dobby, the combination with a bar extending transversely through the lower part 75 of the dobby-frame, and having a series of recesses therein, and a second bar extending transversely through the upper part of the dobby-frame, and having a series of openings therein, of a series of removable guide rods 80 or bars, supported at their lower ends in the recesses on the lower transverse bar and extending at their upper ends through the openings in the upper transverse bar, substantially as shown and described. 85

2. In a dobby, the combination with a bar extending transversely through the lower part of the dobby-frame, and having a series of recesses therein, and a second bar extending transversely through the upper part of the 90 dobby-frame, and having a series of openings therein, of a series of removable guide rods or bars, supported at their lower ends in the recesses on the lower transverse bar, and extending at their upper ends through the openings in the upper transverse bar, and a removable plate extending over the upper ends 95 of said guide rods or bars, substantially as shown and described.

3. In a dobby, the combination with a bar 100 extending transversely through the dobby-frame at the lower part thereof, and having a series of recesses therein, and a second retaining-bar extending transversely through the lower part of the dobby-frame, above the 105 first-mentioned bar, and a third bar extending transversely through the upper part of the dobby-frame, and having a series of openings therethrough, of a series of removable wires or rods, between which the hooks extend, supported at their lower ends in the recesses on the lower transverse bar, and extending at their upper ends through the openings in the upper transverse bar, and a removable plate extending over the upper ends 110 of said guide bars or rods, substantially as shown and described. 115

4. In a dobby, the combination with the pivoted indicator-levers, having upwardly-extending inner ends to engage the lower hooks, and said hooks, and also downwardly-extending portions provided with sockets to receive the lower ends of the lifting-wires of the upper hooks, and said lifting-wires and hooks, of a bar extending transversely through the 120 lower part of the dobby, and having divisions thereon forming recesses to receive the upwardly-extending portions of the indicator-levers, and guide the same, substantially as shown and described. 125

5. In a dobby, the combination with the pivoted indicator-levers, having upwardly-extending inner ends to engage the lower hooks, and said hooks, and also downwardly-extend- 130

ing portions provided with sockets to receive the lower ends of the lifting-wires of the upper hooks, and said lifting wires and jacks, of a bar extending transversely through the lower part of the dobby, and having divisions thereon forming recesses to receive the upwardly-extending portions of the indicator-levers, and guide the same, and a second transverse bar, integral with the first-men-

tioned bar, extending below the downwardly-projecting portions of said indicator-levers, to limit the tilting motion of said levers, substantially as shown and described.
